Primary Examiner — Kelley Donnelly(74) Attorney, Agent, or Firm — Leanne Taveggia Farrell; Westman, Champlin & Koehler, P.A.(57) CLAIM

The ornamental design for a display fixture, as shown and described.

DESCRIPTION

FIG. 1 is a bottom perspective view of a display fixture; FIG. 2 is a top view thereof; FIG. 3 is a bottom view thereof; FIG. 4 is a back view thereof; FIG. 5 is a front view thereof; and, FIG. 6 is an enlarged section view thereof taken through the line indicated in FIG. 5.

The broken lines shown in the drawings are included for purposes of illustrating portions of the display fixture and form no part of the claimed design.
